UNITED STATES PATENT OFFICE.

STANISLAW MARCINIAK, OF BUFFALO, NEW YORK.

STONE-RAKING MACHINE.

1,294,818.

Specification of Letters Patent. Patented Feb. 18, 1919.

Application filed January 14, 1918. Serial No. 211,791.

To all whom it may concern:

Be it known that I, STANISLAW MARCINI-
LAK, a citizen of the United States of Amer-
ica, residing at Buffalo, in the county of

Erie and State of New York, have invented
certain new and useful Improvements in
Stone-Raking Machines, of which the fol-
lowing is a specification.

The primary object of the invention is the
provision of a ready means for picking up
stones in large quantities for transportation,
the device being operable while being for-
wardly propelled over the ground.

A further object of the device is the pro-
vision of a vehicle adapted for gathering
stones from the ground over which the de-
vice travels so that large areas may be
quickly covered in picking the stones there-
from, the vehicle being capable of carrying
large quantities of stones for delivery at a
distance.

A still further object of the invention is
the provision of a stone picker in the nature
of a vehicle that is strong and durable in
construction, easy and inexpensive to manu-
facture and capable of performing the work
of a large number of laborers in an expedi-
tious manner.

In the drawings forming a part of this
application, in which like reference char-
acters refer to corresponding parts through-
out the several views,

Figure 1 is a side elevation of the device,
Fig. 2 is a top plan view thereof,

Fig. 3 is a vertical longitudinal sectional
view of a portion of the device taken trans-
versely through the stone receiver in its filling
position,

Fig. 4 is a similar view with the receiver
in its dumping position.

Fig. 5 is a top plan view of a portion of the
receiver and rake member.

Fig. 6 is a view similar to Fig. 3 including
a showing of the adjacent portion of the ve-
hicle body, and

Fig. 7 is a detail view of a portion of the
receiver adjusting mechanism.

My invention being designed for picking
up stones from the ground and transferring
them to desirable locations, the same broadly
consists of a vehicle 10 having a substan-
tially U-shaped frame 11 arranged with a
horizontal axle 12 at its rear end with ground
wheels 13 positioned thereon and with a sin-
gle forwardly positioned wheel 14 adapted
for turning in steering the device when

drawn forwardly by any suitable draft
means attached to a yoke 15 positioned above
the steering wheel 14.

Forwardly extending arms 16 are jour- 60
naled at their rear ends upon the axle 12
while a stone receiver or drum 17 is jour-
naled to the forward ends of the said arms by
means of trunnions 18 secured to the said
arms with bosses 19 at the ends of the drum 65
journaled upon said trunnions. The drum
17 is arranged with a longitudinal opening
or mouth 20 at one side thereof adapted for
positioning at the top of the drum as shown
in Fig. 3 during the filling operation, the 70
drum being readily inverted as shown in Fig.
4 for dumping the stones from the drum 17.

A rake 21 is also journaled upon the trun-
nions 18, the said rake being in the form of
two rectangular frames 22 perpendicularly 75
arranged with their end members 23 cen-
trally journaled upon the trunnions 18 and
with the connecting sides 24 of the frames
provided with a plurality of substantially
S-shaped hooks 25 slightly spaced apart and 80
extending in the same direction.

A gear 26 is arranged adjacent each end of
the axle 12 within the frame 11 and in-
wardly of the arms 16 in constant mesh with
similar gears 27 secured to the trunnions 18 85
and rake 21 whereby the rake is revolved in
the direction indicated by the arrows in Fig.
1 of the drawings during the forward travel
of the vehicle 10.

Rocker arms 28 are pivoted as at 29 to the 90
sides 30 of the vehicle frame 11 and are con-
nected by links 31 with the arms 16 while
rods 32 connect the rockers 28 with oper-
ating levers 33 arranged at opposite sides of
the vehicle and adjacent the driver's seat 34, 95
the latter being carried by a forwardly ar-
ranged triangular inclined bottom or foot-
board 35 positioned within the forward V-
shaped portion 36 of the frame 11. A spring-
pressed latch 37 is carried by each of the 100
levers 33 for engaging toothed racks 38 ar-
ranged adjacent the bottoms of the levers 33,
said latches being operable by levers 39 in
substantially the usual manner.

It will be seen that the driver positioned 105
upon the seat 34 may control the forward
movement of the vehicle 11 by guiding the
horses, or other draft means attached to the
yoke 15 and by operating the levers 33 may
regulate the position of the hooks 25 with 110
respect to the ground 40 over which the
vehicle 10 is traveling. Any stones which

are positioned upon the ground 40 will be engaged by one or more of the four operative side portions of the rake 21 and the stones picked up by the same and deposited 5 into the open mouth 20 at the top of the receiver 17. It will be understood that the receiver 17 normally maintains its upright position by reason of its own weight and any stones which have been deposited therein 10 and when the drum is filled with stones, the same may be inverted in emptying the stones upon the ground beneath the vehicle.

A body or trailer 41 is arranged with its forward end journaled upon the vehicle axle 15 12 and provided with rear ground wheels 42, the said body having an open top and provided with spaced teeth 43 in its concaved forward end 44 positioned rearwardly 20 of the drum 17. A set screw 45 is arranged for each of the hooks 25 for detachably mounting the hooks upon the sides 24 of the rake. The rake hooks or teeth 25 pass through the openings between the teeth 43 of the forward body 41 and may deposit any 25 stones into the said body which remain upon the hooks after passing the drum mouth 20, while it will be understood that the teeth 43 of the said body wall 41 serve to clean the hooks 25 from the stone during the travel 30 of the hooks between the said teeth. The forward travel of the vehicle 10 operates the rake 21 for gathering the stones upon the ground 40 and elevating the same into the drum 17 and into the body 41, the concaved 35 formation of the teeth 45 insuring a release of all of the stones from the rack 21 which have passed the drum and the deposit of such stones into the body 41.

A large track of stony ground may be 40 quickly cleared of all stones by means of

this device, only one person being required for operating the same and such person positioned upon the seat 34 having complete control of the device.

What I claim as new is:—

1. A stone picker comprising a vehicle having ground wheels secured to an axle, a rotatable rake operatively geared to said axle and provided with rows of hooked teeth spaced apart and projecting in the same direction, manually operable vertical adjusting means for said rake, and a body for the vehicle rearwardly of the rake having a concaved forward end provided with notches forming teeth adapted for the clearing passage of the rake teeth therebetween during the operation of the device upon the forward movement of the vehicle. 45 50 55

2. A device of the class described comprising a vehicle frame, a rear axle journaled in said frame, ground wheels secured to said axle, forwardly projecting arms journaled upon said axle, a rotatable rake comprising rectangular frames journaled upon the free ends of the arms and provided with rows of spaced engaging hooks, gear connections between said rake and said axle, hand levers operatively connected to said arms to vertically adjust said rake, a trailer body pivotally suspended from said axle 60 rearwardly of the rake and provided with a notched concaved forward end forming spaced clearing teeth for said rake hooks, said hooks having a path of movement between said teeth during the rotation of the 65 70 75 rake when the device is operated, and rear ground wheels for said body.

In testimony whereof I affix my signature.

STANISLAW MARCINIAK.

Copies of this patent may be obtained for five cents each, by addressing the "Commissioner of Patents, Washington, D. C."
